UNITED STATES PATENT OFFICE

2,477,111

BUILDING WALL STRUCTURE

Abraham L. Austin, Oak Park, Ill.

Application December 22, 1945, Serial No. 636,848

1 Claim. (Cl. 72—17)

1

This invention relates to a wall structure and method of constructing the same. It especially relates to wall structures for single family residences.

It is well known that there is a great demand for low cost homes which demand is not met by the present type of building construction. Buildings having brick and brick veneer walls have been found to be too expensive for the average home owner. Cement block walls are unsightly and tend to undesirable uniformity and the present shortage of lumber has retarded the building of wood wall homes even where such constructions are permitted.

This invention has for its object a wall of sturdy construction which can be easily erected at low cost from materials which are always available in the open market.

Another object is the erection of a building wall structure which is practically moisture proof which contains insulating elements and is fire resistant. A still further object is the erection of a low cost building wall of pleasing appearance which can be either an outside or inside wall and may be colored to suit the taste of the individual home owner.

I have found that a strong durable low cost wall construction may be built from wall forming insulating or wall board of any desired type which is fastened to the vertical studs in the usual manner to form a wall. The insulating board is then coated with a thin coat of any desired mastic to which is applied a covering of asphalt impregnated roofing paper having mineral granules embedded in its outer or facing surface, the said roofing paper completely covering the wall structure. The roofing paper and granules are then covered by a decorative coated composition which may be of any desired type and color.

The foregoing and such other objects of my invention as may hereafter appear are illustrated in the drawing in which

Fig. 1 is a face view of my new wall structure shown partly in section.

Fig. 2 is a cross section in perspective of a portion of the wall construction taken on line 2—2 of Fig. 1.

Referring to the drawings there is shown the vertically disposed wood frame studs 10 erected in the usual manner to which are attached by any well known fastening means wall forming insulating board 11. The insulating board attached to studs 10 forms an entire wall which is coated with a coat of mastic 12 and covered with the impregnated roofing paper 13. Em-

bedded in the outer or facing surface of the roofing paper 13 are mineral granules 14 of any general uniform size. The roofing paper 13 and the mineral granules 14 are covered with the decorative coating composition 15.

I have found that satisfactory results are obtained by using a wall board such as is now being sold on the market under the trade-mark "Celloflex" an asphalt mastic, roofing paper with 10 granules of the general size of 10 or 12 inch mesh and a decorative coated composition of Portland cement. This makes a wall construction of low cost, easy to construct, of sturdy character, substantially moisture proof, fire resistant and of 15 pleasing appearance.

While I have particularly described a single wall structure, as shown in Fig. 1, I find that the best results are achieved by a double wall construction such as shown in Fig. 2, the outer wall 20 forming the outside wall of the building and the inner wall forming the inside wall of a room. The wall structures being identical, I do not believe any detailed description of the construction of the second wall is necessary. The advantages of the double wall structure are readily apparent to those skilled in the art.

While I have shown and described a particular embodiment of my invention, it will be understood of course that I do not wish to be limited thereto 30 since many modifications may be made which may come within the scope of the present invention for which I claim:

In combination, a double wall structure arranged in parallel relationship on a common 35 plane, a plurality of vertically disposed studs common to both walls, wall forming insulating board attached to the opposite sides of said studs, a layer of mastic on the outer surfaces of said board, asphalt impregnated roofing paper 40 adhering to said mastic, mineral granules embedded in said roofing paper, said roofing paper and granules being covered by a coating of Portland cement.

ABRAHAM L. AUSTIN.
